UNITED STATES PATENT OFFICE.

EDWIN S. VOTEY, OF DETROIT, MICHIGAN.

MECHANICAL ORGAN.

SPECIFICATION forming part of Letters Patent No. 407,801, dated July 30, 1889.

Application filed August 10, 1888. Serial No. 282,450. (No model.)

To all whom it may concern:

Be it known that I, EDWIN S. VOTEY, a citizen of the United States, residing at Detroit, county of Wayne, State of Michigan, have invented a certain new and useful Improvement 5 in Mechanical Organs; and I declare the following to be a full, clear, and exact description of the invention, such as will enable others skilled in the art to which it applies to make and use the same, reference being had to the accompanying drawings, which form a part of this specification.

In the said drawings, Figure 1 is a horizontal section showing parts in plan; and Fig. 2, 15 a front elevation, with parts broken away, of a mechanical organ embodying my invention. Fig. 3 represents mechanism whereby the motor which operates the bellows serves at the same time to feed and rewind the music-sheet.

Heretofore in the construction of mechanical organs or orchestrone in which air is admitted to the reeds through perforated music-sheets wound upon rolls it has been customary to operate the air-bellows and draw the 20 sheet off by hand, and subsequently to rewind it by hand, or to do the same through the medium of a foot-treadle. So, also, a foot-treadle has been employed to pump air, as a reed-organ is pumped, and this air has been 25 fed through an air-motor for the same purpose; but in these cases the labor involved is very considerable, and the instrument is not capable of the fine gradations or modulations of sound which would result from a more direct and steady control of the propelling power.

It is the purpose of my invention to combine with a mechanical organ or orchestrone of this character an electric motor for operating the bellows; also, in the provision of means whereby the paper may be fed and after having been expended may be rewound either by the same or another motor; also, in the combination, with the mechanical organ or orchestrone and its feeding-motor, of a rheostat and a stop, governable either by the hand or the foot, whereby the rheostat may be manipulated at the will of the operator, and through it the speed of the motor be 40 steadily and effectually governed and accelerated or retarded at the will of the operator.

To this end, A represents any mechanical organ or orchestrone. B is its music-roll, and B' the perforated music-sheet.

C is an electric motor, geared by any convenient means with the mechanism for operating the bellows.

D is a rheostat, and E a stop adapted to be operated by the hand for controlling the said rheostat, although I would have it understood that this rheostat might be arranged to be governed by the foot.

The orchestrone or mechanical organ may be provided with suitable stops and corresponding mechanism for regulating the speed 65 with which the sheet is fed from the roll, and with other mechanism whereby the paper may be rewound upon the roll. My invention is independent of any particular means for accomplishing these ends. It may be accomplished by an independent electric motor F, for feeding the paper from the roll and for rewinding the same, and in this case the feeding of the roll becomes absolutely independent 70 of the speed of the motor which operates the bellows, and the electric motor F may or may not be provided with an independent rheostat for governing its speed, and by this arrangement of independent motors the operator is enabled, through the medium of the 75 rheostat or rheostats, by changing and graduating the speed of the motor, to modulate the volume of sound to any desired degree. He may without changing the speed of the music-sheet modulate the volume of sound from full 80 volume, due to a full bellows, down to a subdued volume, due to almost an exhausted bellows, and in this way may be produced effects not attained hitherto in instruments of this character, and may thus change the volume 85 or amplitude of the sound without altering its quality, as the same would be altered by any mechanism in the nature of a swell. On the other hand, with an independent motor F for feeding and rewinding the music-roll, the rate 90 of feed may be governed entirely independent of the speed of the motor which operates the bellows, and this regulation of the feed may in like manner, if desired, be accomplished by the rheostat F.

While the apparatus may be provided with independent motors for the bellows and for

feeding and rewinding the paper roll, the same may be accomplished through the medium of a single motor, as shown in Fig. 3, in which G is a disk provided with a band-seat, whereby it may be geared by suitable belting, or otherwise, to the motor C, by which the bellows are operated. This disk G is brought into frictional engagement with a disk H, connected directly or indirectly with the roller B. A suitable stop H' is provided, whereby the disk H may be moved forward or backward. It is manifest that by bringing the disk H forward, so that it engages the disk G close to its periphery, it thereby imparts a rapid motion to the music-roll B, while the shifting of the disk H nearer to the center of the disk G will decrease the speed of the music-roll in a corresponding degree, and in this way the rate of feed of the music-sheet may be governed at the will of the operator at all times. After the music-sheet has been expended the disk H may be pushed to the opposite side of the shaft g. This will give to the disk H a reverse motion, and so rewind the music-sheet at any speed the operator may desire. In mechanical organs or orchestrone it is usually desirable that the wind-pressure be maintained quite full, in order to properly operate the pneumatic valves, and for this reason the motor which operates the bellows is usually kept at pretty full speed. In constructions of this character the mechanism shown in Fig. 3 is particularly applicable; but even with this construction the operator may modulate the volume of sound by varying the speed of the motor C through the medium of the rheostat, and at the same time regulate the feed of the music-sheet by the stop H'.

Electric motors have been used heretofore in which means are provided for cutting out part of the coils of the field-magnet and inserting an equivalent number of resistances in the circuit of said magnet. An electrical piano has also been used having strings tuned to different pitches, and electrical-impulse-giving devices arranged to act electrically upon the strings to cause them to vibrate with one or more rheotomes for producing a vibratory current. I make no claim to either of these inventions.

What I claim is—

1. In a mechanical organ, the combination, with the paper-feeding mechanism, of an electric motor, a rheostat, and a stop, whereby more or less resistance may be inserted in the circuit at will to vary the speed of the paper, the bellows being operated by independent means, substantially as described.

2. In a mechanical organ, the combination, with a rotatory disk geared to the motor, of a disk having its axis at right angles to the first disk and bearing with its periphery against the flat face of the latter, means for adjusting said disk to have its frictional contact with the first disk at different points upon the flat face of the latter between the shaft and the edge, and a pulley on the shaft of the frictionally-driven disk geared to the music-roll or paper-feeding roll, substantially as described.

In testimony whereof I sign this specification in the presence of two witnesses.

EDWIN S. VOTÉY.
